UNITED STATES PATENT OFFICE.

HANS P. PETERSEN, OF SOUTH TACOMA, WASHINGTON.

DRAFT APPLIANCE.

1,073,516.

Specification of Letters Patent. Patented Sept. 16, 1913.

Application filed December 6, 1912. Serial No. 735,346.

To all whom it may concern:

Be it known that I, HANS P. PETERSEN, a subject of the King of Denmark, residing at South Tacoma, in the county of Pierce and 5 State of Washington, have invented certain new and useful Improvements in Draft Appliances, of which the following is a specification.

This invention relates to improvements in 10 draft appliances for railway cars, and particularly to draft bar connections.

An object in view is the facilitating of the application of the draw bar to the draft beam connections and the efficient locking 15 of the parts in their given positions, while providing for the requisite reciprocal and lateral play of the draw bar.

With this and further objects in view, as will hereinafter in part become apparent 20 and in part be stated, the invention comprises the combination with draft beams, of a draw bar adapted to extend therebetween, stops connected to the draft beams and surrounding the draw bar, follower plates carried by and movable along the draw bar between the stops, springs pressing the plates against the stops, and a detachable locking sleeve retaining the draw bar against release from the follower plates.

30 The invention further comprehends the combination, with draft beams and cross stops, of a draw bar extending between the draft beams and past the stops, follower plates carried by the draw bar, spacing 35 springs engaging the follower plates, a shouldered sleeve adapted to retain the draw bar against displacement relative to the follower plates, and a locking sleeve detachably engaging the draw bar for retaining 40 the first mentioned sleeve in position.

The invention further comprehends certain other novel constructions, combinations and arrangements of parts, as will be hereinafter described and claimed.

45 In the accompanying drawing: Figure 1 is a longitudinal, vertical section through draft apparatus embodying the features of the present invention. Fig. 2 is an inverted plan view thereof. Figs. 3, 4, 5 and 6 are 50 transverse, vertical sections taken on the planes indicated respectively by lines 3-3, 4-4, 5-5 and 6-6 of Fig. 1 and looking respectively in the directions indicated by the arrows. Fig. 7 is an end view of the 55 locking sleeve detached. Fig. 8 is an end

view of the draw bar detached, the sleeves being omitted. Fig. 9 is a longitudinal, vertical, central section through a modified embodiment of coupler bar and locking sleeve.

Referring to the drawing by numerals, 1 60 indicates the flooring of the superstructure of a car which may be of any type and provided with the usual sub-structure, not illustrated, and with the usual draft beam, not shown, with which latter are connected the 65 draft sills 2, 2, which may be disposed in conventional arrangement relative to the draft beam and body bolster, the latter also not being illustrated. The beams 2 are spaced apart and are connected at various 70 points along their length by cross webs forming stops 3, 3. The outermost stop 3 is preferably disposed immediately in the rear of the buffer block 4 and consists preferably of cross plates 5, 5, one having its 75 ends fixed to the respective sills 2 at their lower edges and the other having its ends fixed to the sills 2 at their upper edges, and each being bent intermediate its ends toward the other and connected by spaced 80 flaps or metal strips 6, 6 having their ends fixed to the cross plates 5, the plates 5 and 6 thus forming a rectangularly inclosed space through which extends the draw bar 7 which is preferably rectangular in cross section 85 throughout that portion of its length extending through the opening between the plates 5 and 6. Each of the other two stops 3 is made up of upper and lower cross pieces or 90 plates 8, 8 connected at their ends to the respective upper and lower portion of the beams 2, and the cross pieces 8 being in turn connected by connecting pieces 9, the latter being arcuate in form and conforming to 95 curved portions of the pieces 8, which curved portions, with the plates or connecting pieces 9, provide a circular closure through which the draw bar 7 extends, the draw bar being cylindrical throughout those 100 portions of its length extending through the stops 3, 3 in the rear of the outermost stop 3. The cross sectional area of the draw bar 7 is reduced just inside the outermost stop 3, forming an abutting shoulder 10, and the portion of the draw bar in the rear of the 105 shoulder 10, beginning at the shoulder, is cylindrical and of uniform diameter for a length sufficient for extending from the outermost stops 3 to the intermediate stop 3, and thereat the draw bar 7 is formed with 110

an annular shoulder 11 and extends thence rearwardly in the form of a reduced cylinder.

An annular sleeve 12 surrounds the draw bar 7 in the rear of and extending from the shoulder 11 to the rearmost stop 3, the forward end portion of the sleeve extending within and across the intermediate stop 3 and being formed with an enlargement 10 producing an annular shoulder 13 extending radially outside of the periphery of the contiguous portions of the draw bar 7 and also forming an annular shoulder 14, the annular shoulder 13 facing forwardly at 15 one side of the intermediate stop 3 and the annular shoulder 14 facing rearwardly at the other side thereof.

Adjacent the rear end of the draw bar 7 the bar is formed with an annular groove 20 15 and longitudinal slots 16, 16 extending from the groove to the end of the draw bar, the slots 16 being of a width sufficient for leaving radial lugs or projections 17, 17, in the preferred embodiment each lug 17 being 25 of a width circumferentially of the draw bar equal approximately to the width of each groove 16 circumferentially of the draw bar.

Mounted on the rear end portion of the draw bar 7 is a retaining or locking sleeve 30 18 which has its free end portion of a diameter adapted to loosely fit the opening formed through the rearmost stop 3, such diameter being sufficiently great for providing a circumferential shoulder 19 at the forward 35 end of the sleeve 18 outstanding radially from the sleeve 12. The sleeve 18 is preferably tapered rearwardly or inwardly as at 20 so as to facilitate reciprocation through the stop 3. The bore of the sleeve 18 is 40 substantially equivalent in diameter to the diameter of the rearmost portion of the bar 7 so as to surround the same, and the sleeve is provided with radially inwardly extending lugs 21, 21 corresponding in width approximately to the dimensions of the lugs 45 17 and of a length approximately the same as the width of the groove 15, said lugs being thus adapted to snugly fit the groove and at the same time to be free to revolve 50 therein. Thus in applying the sleeve 18 to the rear end of the draw bar 7 the sleeve may be projected axially onto the draw bar with the lugs 21 disposed to travel longitudinally of the grooves 16 until the lugs 55 55 strike against the forward shoulder of the groove 15, whereat the sleeve is adapted to be revolved until the lugs 21 are alined axially with the lugs 17 and are thereby locked against longitudinal withdrawal 60 from the draw bar. To prevent the sleeve 18 from becoming accidentally revolved to a position of registration between the lugs 21 and the grooves 16 a pin 22 is passed through the tapered portion of the sleeve 65 18 and through the rear end portion of the

draw bar, the sleeve and draw bar being formed with apertures adapted to register when the lugs 21 are alined with and forward of the lugs 17. The pin 22 terminates inside the longitudinal planes of the greatest diameter of the sleeve 18 so as to be free to readily reciprocate through the rearmost stop 3.

Immediately in the rear of the outermost stop 3 a follower block 23 is mounted on the larger cylindrical portion of the draw bar 7 and immediately in front of the intermediate stop 3 is a similar follower block 24, each of said blocks being preferably provided with a sleeve extending toward the other along the draw bar for guiding and confining the respective parts. Surrounding the draw bar between the follower blocks 23 and 24 are nested coil springs 25 and 26 disposed to have their ends engage 80 the respective follower blocks, the follower block 24 being disposed to engage the shoulder 13 of sleeve 12 and the follower block 23 being disposed to engage the shoulder 10 of draw bar 7. Surrounding the sleeve 90 12 are follower blocks 27 and 28 similar in construction and arrangement to the blocks 23 and 24, block 27 engaging the shoulder 14 of the sleeve 12 and the block 28 engaging the annular portion or shoulder 19 of sleeve 18. Nested coil springs 29 and 30 are disposed between the follower blocks 27 and 28 and have their opposite ends engaging the respective blocks.

As best seen in Figs. 3, 4 and 5, the stops 100 3 constitute guideways for the respective parts of the draw bar 7, and the openings formed by the said stops are preferably slightly enlarged laterally, as indicated in the last named figures, for permitting a certain amount of radial swing of the draw bar.

In operation, draft stresses are delivered from the knuckle through the bar 7 to the sleeve 18 and thence to sleeve 12 and from the shoulder 19 of sleeve 18 to the follower block 28 and thence through springs 29 and 30 to follower block 27 and to the intermediate stop 3, while at the same time a draft stress is transmitted also through the sleeve 115 12 to the shoulder 13 thereof and thereby to the follower block 24 and thence to the springs 25 and 26 and to the follower block 23, which delivers the stresses to the outermost stop 3, the stops delivering the draft 120 stresses to the draft beams 2 and thence to the car structure. The buffing stresses delivered to the draw bar and the compression stresses also delivered thereto are transmitted through shoulder 10 to the follower 125 block 23 and thence through the springs 25 and 26 to follower block 24 and to the intermediate stop 3, such stresses being at the same time also transmitted from the shoulder 11 to the sleeve 12 and thence through 130

the shoulder 14 to the follower block 27, springs 29 and 30 and follower block 28 to the innermost stop 3, stresses being delivered from the stops to the same parts as above-5 said.

In Fig. 9 I have illustrated a modified embodiment in which the draw bar 7' is provided with a locking sleeve 18', the draft bar and sleeve being similar in construction 10 and arrangement to the draw bar 7 and sleeve 18 but differing therefrom in that a plurality of the locking lugs arranged in longitudinal series is provided. In this embodiment the rear end portion of the draw 15 bar 7' is provided with spaced annular grooves 15' and diametrically oppositely disposed longitudinal grooves 16' connecting the grooves 15' and extending from the rearmost grooves to the extreme end of the 20 draw bar, the grooves 16' leaving radially disposed locking lugs between the end of the bar and the first groove 15' and between each two of the grooves 15'. The sleeve 18' is provided with radially inwardly ex-25 tending arcuate locking lugs 21' disposed at diametrically opposite points of the bore of the sleeve in position for being adapted to slide longitudinally within the grooves 16' and then to be moved circumferentially 30 by a rotary movement of the sleeve 18' to a position axially aligned with the lugs of the draw bar, whereby the sleeve 18' is adapted to be locked onto the draw bar. A pin 22' is disposed to extend through a portion of 35 the sleeve and draw bar to prevent any relative rotary movement of the parts tending to allow the locking lugs of the sleeve to move into register with the grooves 16'.

Having thus described the invention, what 40 is claimed as new is:

1. In draft apparatus, the combination of a draw bar having a plurality of shoulders, a draft stress transmitting element engaging one of the shoulders, a sleeve mounted on the 45 draw bar and engaging another of the shoulders, and formed with extension means pro-

viding a shoulder, stress transmitting means engaging the last mentioned shoulder, and a sleeve detachably connected to the draw bar in position for retaining the first men-50 tioned sleeve thereon.

2. In draft apparatus, the combination, with draft beams, of stops extending between and connecting said draft beams, a draw bar extending through said stops, 55 said draw bar being formed with a shoulder adjacent one of the stops, a sleeve mounted on the draw bar and formed with a shouldered portion adjacent another of the stops, means for retaining the said sleeve on 60 the draw bar, and stress transmitting means adapted to engage the shoulder of the draw bar and the shouldered portion of the sleeve.

3. In draft rigging, the combination, with draft beams, of cross stops connecting the 65 same and each comprising upper and lower cross plates and spaced connecting plates connected to said cross plates, the draw bar extending through said stops between the upper and lower and spaced plates thereof, 70 and means for transmitting stresses from the draw bar to the stops.

4. In draft rigging, the combination, with draft beams, of cross stops connecting the 75 same and each comprising upper and lower cross plates and spaced connecting plates connected to said cross plates, the draw bar extending through said stops between the upper and lower and spaced plates thereof, and means for transmitting stresses from 80 the draw bar to the stops, the said spaced connecting plates being spaced a distance sufficiently greater than the cross sectional dimension of the draw bar for allowing 85 radial swing thereof.

In testimony whereof I affix my signature in presence of two witnesses.

HANS P. PETERSEN.
